UNITED STATES PATENT OFFICE.

ERNEST LESCHHORN, OF CHICAGO, ILLINOIS, ASSIGNOR TO LATHAM MACHINERY COMPANY, A CORPORATION OF ILLINOIS.

WIRE-STITCHING MACHINE.

Application filed September 4, 1923. Serial No. 680,763.

This invention relates to a wire stitching machine and more particularly to the feeding and cutting mechanism thereof.

One of the objects of the present invention 5 is to provide a stitching machine of simple construction and at the same time increase the efficiency of the same.

A further object of the invention is to 10 provide a novel and simple means for adjusting the feeding and cutting mechanism by means of which the machine can be quickly adjusted to stitch various sized staples.

A still further object of the invention is 15 to provide a novel form of cutting mechanism by means of which the knife is always actuated through the same cutting movement by the actuating mechanism regardless of its position of adjustment.

20 These and other objects are obtained by providing a construction and arrangement of the various parts in the manner herein-after described and particularly pointed out in the appended claims.

25 Referring to the drawings:

Fig. 1 is a front elevational view of a wire stitching machine showing my improvement embodied therein.

30 Fig. 2 is an enlarged cross sectional view taken on lines 2—2 of Fig. 1.

Fig. 3 is an enlarged detail top plan view of my improved feeding mechanism showing the train of gears for operatively driving the same.

35 Fig. 4 is an enlarged cross sectional view taken on the lines 4—4 of Fig. 1.

Fig. 5 is an enlarged cross sectional view 40 taken on the lines 5—5 of Fig. 1, showing the manner in which my improved cutting mechanism is adjustably mounted on the frame of the machine.

Fig. 6 is an enlarged cross sectional view taken on the line 6—6 of Fig. 1.

Fig. 7 is an enlarged fragmentary front 45 elevational view of the cutting mechanism.

Fig. 8 is a rear elevational view of the cutting mechanism shown in Fig. 7.

Fig. 9 is a cross sectional view of the cutter box taken on the lines 9—9 in Fig. 7.

50 Fig. 10 is a cross sectional view taken on the lines 10—10 in Fig. 8.

Fig. 11 is an enlarged cross sectional view taken on the lines 11—11 of Fig. 1.

Fig. 12 is an enlarged cross sectional view taken on the lines 12—12 of Fig. 1 and 55 looking in the direction of the arrows indicated, and

Fig. 13 is an enlarged side elevational view, taken on the lines 13—13 of Fig. 1 and looking in the direction of the arrows, of 60 the wire check and straightening device.

The present invention is applied to wire stitching machines of the general character well known in the art and only that portion of the machine is shown in the drawings to 65 sufficiently illustrate the present invention and its relative parts. The whole stitching mechanism, which constitutes the head, is supported on a horizontally disposed arm 15, which rotatably supports a shaft 16 in 70 a horizontal bore 17 of the arm. Secured to the forward end of the arm 15 is a vertically disposed plate 18 upon which the operative parts of the stitcher are mounted. A reduced portion of the shaft 16, indicated 75 at 19, extends from the plate 18 and has secured thereto by means of a key, not shown, an operating cam 20. The cam 20 is prevented from displacement on the reduced portion 19 of the shaft 16 by means of a washer and screw 21. Securely mounted in any well known manner on a collar 22 formed integrally with the cam 20 is a spur gear 23, as clearly shown in Fig. 2. The lower portion of the plate 18 has secured thereto by means of pins 24, a block 25. The block 25 is provided with a vertically extending groove or recessed portion 26 on its front side through which the staple former 27 is mounted for vertical sliding movement. 80 The forward or front side of the staple former 27 is provided with a vertically extending channel or groove 28, which is adapted to reciprocally receive a staple driver 29. Both the staple former and driver are operatively reciprocated in their respective channels or grooves by the cam 20. The staple former 27 is connected to the cam by a roller 30 at its upper end, which operates in a cam groove 31 formed 85 in the cam, and the driver 29 is operatively connected to the cam by means of a pitman

90 The forward or front side of the staple former 27 is provided with a vertically extending channel or groove 28, which is adapted to reciprocally receive a staple driver 29. Both the staple former and driver are operatively reciprocated in their respective channels or grooves by the cam 20. The staple former 27 is connected to the cam by a roller 30 at its upper end, which operates in a cam groove 31 formed 95 in the cam, and the driver 29 is operatively connected to the cam by means of a pitman 100

connection 32 having one end thereof connected to the upper end of the driver and the other end thereof pivotally connected eccentrically to the cam 20. Extending 5 through apertures 33 and 34 formed in the lower ends of the block 25 and the plate 18, respectively, is the usual anvil 35 mounted in a socket 36, which is secured in the said apertures 33 and 34 by a set screw 37. The 10 anvil 35 is normally actuated to the position shown in Fig. 2 by a compression spring 38 which has one end thereof engaging a shoulder 39 of the anvil 35 and the other end thereof engaging the base of the socket 15 36. The forward end of the anvil is provided with the usual horizontally disposed slot 40, which is adapted to receive the wire and hold the same during the time the staple is being formed by the staple former. Pivoted 20 forwardly of the anvil 35 is the usual staple supporter 41 pivoted at 42 to a hanger 43. The supporter 41 is adapted to extend between the legs of the staples while they are being driven. The supporter 41 is normally 25 held in the position shown in Fig. 2 by a vertically reciprocable pin 44 mounted in a socket 45 and normally pressed downwardly by a compression spring 46.

The mechanism thus far described is the 30 usual mechanism employed in this type of stitching machine, and per se does not form any part of the present invention.

For this reason a more detailed description of the same is unnecessary.

35 The principal feature of the present invention is the provision of an improved cutting mechanism which is adapted to be adjusted by a thumb screw in such a manner as to cut wires of different lengths when the 40 feeding mechanism is correspondingly adjusted to feed wires of a proper corresponding length. This mechanism comprises an adjustable cutter box 47, which includes a block 48 having a rearwardly projecting portion 49 adapted to slidably engage a horizontally extending recess 50 formed on the forward side of the block 25. The block 45 48 is provided with a threaded aperture 47' which is adapted to receive a bolt 48' for 50 permanently securing the box against relative horizontal adjustment when the proper adjustment of this cutter box has been determined. This bolt 48' extends through a slotted aperture 49' of the plate 18 and block 55 25. It will, of course, be understood that when the cutter box is to be adjusted horizontally this bolt 48' must be loosened so as to permit this adjustment. The cutter box 47 is adjustably mounted in the groove 50 by means of a threaded screw 51. The 60 threaded screw 51 connects the adjustable cutter box 47 by having threaded engagement therewith, as shown at 52. The end of the screw 51 opposite the threaded end 65 thereof extends through a horizontally dis-

posed aperture 53 in the block 25, as clearly shown in Figs. 2 and 6. The externally projecting portion of the threaded screw has securely fixed thereto by means of a pin 54 a thumb engaging portion 55. The screw 70 51 is normally held against displacement from the block 25 by a collar 56 formed integrally with the screw 51.

From this construction it will be seen that as the screw 51 is turned through the medium of the thumb engaging portion 55, the 75 cutter box 47 may be horizontally adjusted to and from the staple forming and driving mechanism.

Secured to the block 48 by means of a 80 shoulder 57' of a screw bolt 65 is a second block 58. Secured to the block 58 by means of a screw 59 is a wire tube support 60. Removably secured in the support 60 by means of a set screw 63' is a wire guide tube 85 60'. Positioned on the front face of the cutter block is a plate 61 secured in position by a screw 62 and having an aperture 62' embracing the head of the bolt 65. Reciprocally mounted between the plate 61 and the second block 58 is a knife carrying member 63. The knife carrying member 63 is provided with a slotted aperture 64 which slidably engages an enlarged portion 57 of the screw 65. The knife carrying member 95 63 is further provided with a pin 67 secured thereto in any well known manner and having its forward edge extending forwardly and adapted to reciprocate in a slot 68 formed in the plate 61. This pin normally 100 engages the upper portion of the slot and limits the upward movement of the reciprocating knife carrying member 63 in its normal operation. Mounted on the side adjacent the staple former is a reversible knife 105 69 which is slightly bevelled at both ends thereof, as shown at 70, in such a manner as to present a good cutting edge. This knife 69 is provided with, on one side thereof and intermediate its ends, a projecting portion 110 71, which is adapted to engage in a horizontal channel 72 formed on the side of the knife carrying member 63 adjacent the staple forming and driving mechanism. The projection 71 of the knife 69 is secured in the channel 72 of the member 63 by means of a screw 73. By this construction, it will 115 be seen that the knife is securely held in its position so as to insure its efficient operation.

120 From this construction it will be seen that as soon as one edge of the cutter knife 69 has become dull the knife may be inverted and a new cutting edge used in cutting the wire.

125 The reciprocating knife 69 together with the knife carrying member 63 is normally actuated to its uppermost position by a compression spring 74 which is seated in a bore 75 formed in the second block 58. The 130

knife carrying member 63 is guided in its vertical reciprocating movement by a tubular member 76 secured to a bearing plate 77, which, in turn, is secured to the knife carrying member 63 by means of screws 78. By this construction, it will be seen that the tubular member embraces the spring 74 and has its outer wall slidably engaging the bore 75 of the block 58 in a manner to insure absolute vertical reciprocation of the knife carrying member 63 and also to prevent the possibility of the knife cutting the wire at an angle by reason of wear in these reciprocating parts. In order to further insure the absolute vertical reciprocation of the knife and the carrying member, it will be seen by referring to Figs. 6 and 11 that the knife carrying member is provided with a channel 79 extending vertically throughout the length of this member and engageable with a corresponding projection 80 formed on the forward side of the block 58.

In connection with my improved wire cutting mechanism I have provided a novel adjustable feeding mechanism by means of which the lengths of wire fed may be varied with the least possible effort on the part of the operator. This improved mechanism comprises feeding rolls or discs 81 and 82, respectively, which are operatively driven through a train of gears 83, 84 and 85, the first of these gears 83, of course, being operatively driven by the gear 23 secured to the operating cam 20. The gears 83 and 84 are pivotally supported on the studs 87 and 88 secured to the plate 18 of the head of the stitcher. The roller 81 is operatively driven by the gear 84 and is secured thereto by a collar 89 extending from the gear to the feed disc or roller 81. The feed roller or disc 82 is pivotally mounted in a bracket 90, which, in turn, is pivotally secured to the plate 18 by means of a stud screw 91. The feed roller or disc 82 is resiliently pressed against its corresponding feed disc or roller 81 through a compression spring 92, which normally engages the free end 93 of the pivoted bracket 90. The tension on the spring 92 may be adjusted by a thumb nut 94, which is threaded to a pivoted bolt 95, which, in turn, is secured to a boss 96 formed on the plate 18. The feed roller 82 is frictionally secured to a shaft 97, which is journaled in the bracket 90. The shaft 97 is provided with an enlarged collar portion 98 having one side thereof engageable and bearing against the bracket, as shown at 99, and the other edge thereof engageable with the rear side of the feed roller 82 as shown at 100. Extending through the feed roller 82 and formed as an integral part of the shaft 97 is a reduced portion 101. This reduced portion projects slightly beyond the front surface of the roller 82 as shown at 102. The feed roller 82 is frictionally secured to the

shaft 97 by means of a washer 103, which is provided with a depression 104 and an annular projecting rim 105. Extending through the washer 103 and in threaded engagement with the longitudinally threaded bore 106 in the shaft 97 is a bolt 107.

From the above description it will be understood that the tightening of the bolt 107 compresses the annular rim 105 of the washer 103 and frictionally clamps the feed roller 82 between this washer and the enlarged collar portion 98 of the shaft 97. In order to maintain the washer 103 in relatively fixed position with respect to the shaft 97, I have provided a pin 108, which extends through the washer 103 and into the shaft 97 as clearly shown in Fig. 4. This prevents any rotation of the washer 103 with respect to the shaft 97. The object of this construction is to permit the washer to carry certain graduations as shown at 109 in Figs. 1 and 3 with a single indicating mark on the front surface of the roller 82 adjacent the graduating marks on the washer. By this arrangement the bolt 107 may be loosened and the feed roller 82 may be adjusted so that a certain graduation will permit the feeding of a predetermined length of wire to the staple and forming mechanism. The thumb engaging portion 55 has a corresponding graduation provided at 110 by means of which the cutter box may be adjusted with respect to the staple former so as to be positioned in such a manner that when the feeding mechanism and the cutting mechanism are adjusted to corresponding graduations, the wire fed by the feeding mechanism will be cut so as to be formed into staples in which the legs are of equal length. It will, of course, be understood that each of these two feed rollers, that is, roller 81 and roller 82, are provided with the usual projecting feeding cam surface 81' and 82', respectively, and that when the roller 82 is adjusted with respect to the roller 81 the length of wire fed will vary in accordance with the relative adjustment of these two rollers.

The mechanism for actuating the cutting mechanism during each cycle of operation will next be described.

This mechanism comprises an arm 111 having one end thereof pivoted at 112 to the plate 18. The free end of this arm 111 is provided with a roller 113, which is positioned to the rear of this arm, and is adapted to engage a cam 114 formed on the outer surface of the cam member 20, as clearly shown in Figs. 1, 2 and 3. Positioned on the free end of the arm 111 adjacent the roller 113 is a threaded barrel portion 115, which is adapted to receive a threaded bolt 116 with the head 117 thereof extending downwardly and in engagement with the bearing plate 77, in a manner to actuate the cutter knife 69.

and knife carrier 63 in cutting the wire fed to the staple forming and driving mechanism. The bolt 116 may be adjusted to compensate for wear in these wearing parts and 5 also to permit the proper adjustment when the cutting edges of the knife are ground. The bolt 116 is securely held in its adjusted positions in the threaded portion 115 of the arm 111 by a lock nut 118.

10 By the construction of the above described actuating mechanism for the cutting mechanism, it will be understood that the cutter box may be adjusted horizontally through the medium of the thumb screw 55, and in 15 all positions of adjustment, the cutting mechanism will always be actuated through the same cutting movement, regardless of its relative adjusted position.

The wire 119 from which the staples are 20 formed is taken from the usual spool 120 carried on the spindle 121 supported on the arm 122, which projects from and is formed integrally with the plate 18. From the spool 120 the wire is fed over the curved member 25 123 down through a straightening device 124 and then through a guiding member 125. After passing through the guiding member 125 it is engaged by a checking member 126, which is adapted to prevent the withdrawal 30 of the wire after once it has been fed past the feed rolls. From the checking member it passes down between the feed rollers or discs 81 and 82 and then through a curved feeding tube 127. From the feeding tube 35 it is passed through a wire guiding tube 60' into the staple forming and cutting mechanism wherein it passes into the groove 40 formed in the forward end of the anvil and there held until the staple former forms the 40 wire into a staple and the driver drives it into the material. The general construction above described of feeding the wire is the usual one employed in this type of wire stitching machine and the general construction 45 per se does not form any part of the present invention, excepting so far as the improved means heretofore described may be employed in quickly adjusting the machine to drive staples of different lengths.

50 The wire straightening device shown in Fig. 13 and indicated by the numeral 124 is adjustably mounted in a boss or bearing portion 129, which is provided with a longitudinally extending bore 130, which slidably 55 receives an adjustable member 131 having one end thereof threaded and adapted to receive a thumb nut 132 for laterally adjusting the adjustable member in the bearing portion 129. The adjustable member 131 is normally pressed outwardly by a compression spring 133. On the end of the member opposite to the end to which the thumb nut 132 is secured I have provided oppositely disposed straightening rolls 134 between 60 which the wire is fed and by adjust-

ing this thumb nut 132 these rolls 134 may be laterally adjusted so that proper straightening of the wire can be readily had. It will be understood, of course, that immediately above these wire straightening 70 rolls 134 are two permanently fixed pins 135, between which the wire passes. These pins are secured to an extension of the side plate 18 and when the rollers are adjusted laterally with respect to these pins 135 the wire is 75 readily straightened.

In order to permit the cutter knife 69, together with its carrying box 47 to be adjusted from one side of the staple former 27, it has been necessary to provide a vertically extending plate 56' which projects 80 forwardly and engages one leg of the staple former 27 for the purpose of preventing the leg of the former from spreading, as clearly shown in Figs. 6 and 12. The member 56' 85 is of course secured to the block 25 in any well known manner, preferably by screws 27', and thus forms a lateral bearing for the reciprocating staple former.

From the above description, it will be seen 90 that I have provided a very efficient wire stitching machine and one in which the feeding mechanism and the cutting mechanism may be correspondingly adjusted by adjusting each of these parts to their corresponding 95 graduations to stitch staples of various sizes with the least possible effort on the part of the operator, and thereby saving considerable time and trouble in adjusting these machines to stitch staples of various sizes. 100

While in the above description, I have described one embodiment which my invention may assume in practice, it will of course be understood that the construction herein shown is capable of modification and that 105 modification may be employed without departing from the spirit and scope of my invention as expressed in the following claims.

What I claim as my invention and desire to secure by Letters Patent is:

1. A wire stitcher comprising a frame, wire feeding mechanism carried thereby, horizontally adjustable and vertically reciprocable cutting mechanism carried by said frame for cutting the wire fed by said feeding mechanism, and actuating means for said cutting mechanism including an arm pivoted to said frame and a screw adjustable in said arm for varying the vertical movement of said cutting mechanism. 110

2. In a wire stitcher, the combination with a frame, of a drive shaft mounted thereon, a wire feeding mechanism operatively driven by said shaft, a staple former mounted in said frame for vertical reciprocatory movement, a staple driver mounted in said staple former for vertical reciprocatory movement, a cam secured to said shaft and operatively connected to said staple former and driver, cutting mechanism mounted on 120 125 130 135 140

said frame and adjustable horizontally with respect to said staple former and driver, and an arm pivoted to said frame having a roller on one end thereof engageable with said cam for actuating said cutting mechanism, an adjustable screw on said arm adjacent said roller adapted to engage said cutting mech-

anism, and means for locking said screw in its adjusted positions.

In testimony whereof I have signed my name to this specification, on this 29th day of August, A. D. 1923.

ERNEST LESCHHORN.
